DESIGN FOR A GLOVE

William O. Wells, Jr., Evanston, Ill.

Application August 16, 1941, Serial No. 102,906

Term of patent 14 years

To all whom it may concern:

Be it known that I, William O. Wells, Jr., a citizen of the United States, residing at Evanston, in the county of Cook, State of Illinois, have invented a new, original, and ornamental Design for a Glove, of which the following is a specification, reference being had to the accompanying drawing, forming a part thereof.

Fig. 1 is a front view of a glove showing my design, the thumb portion being turned back; and

Fig. 2 is a rear view of the glove shown in Fig. 1.

I claim:

The ornamental design for a glove, as shown.
WILLIAM O. WELLS, JR.
